DEODORIZING AND DISINFECTING DEVICE

Lewis Cathcart, Chicago, Ill.

Application March 21, 1939, Serial No. 263,307

6 Claims. (Cl. 21—119)

This invention relates to vaporizers and more particularly to an electrical fumigating device to be used for disinfecting and deodorizing purposes, more especially in the home, but being efficient and practical for use in hospitals and the like, and in various public places in general where disinfecting or deodorizing is necessary or desirable.

The object of the invention is to attain simplicity and compactness of structure and economy in manufacture, together with practicability and efficiency in operation and use, as well as durability.

With the foregoing and other objects and advantages to be attained, as will hereinafter more fully appear, the invention consists in the general structure and in the particular parts and combinations and arrangements of parts thereof as set forth in the following description and appended claims, reference being had to the accompanying drawings illustrating a practical adaptation of the invention, in which—

Figure 1 is a view of the device partly in front elevation and partly in vertical section;

Figure 2 is a vertical section of the device, on an enlarged scale;

Figure 3 is a detail perspective view of the vaporizing receptacle detached;

Figure 4 is a horizontal section on the line 4—4 of Figure 2;

Figure 5 is a horizontal section on the line 5—5 of Figure 2;

Figure 6 is a fragmentary view in section similar to the lower portion of the structure shown in Figure 2 but illustrating the dispensing element in elevation and certain parts of the electric connecting elements in section;

Figure 7 is a fragmentary section taken on or about the line 7—7 of Figure 6;

Figure 8 is a perspective view of the dispensing element detached; and

Figure 9 is a fragmentary perspective view illustrating the plug element of the electric cord.

Referring now to the drawings, the numeral 1 designates the hollow body of the device which, as shown, is generally cylindrical, but, obviously, may be of any desirable form and made of either opaque or transparent material, as preferred. If made of opaque material as a substantial whole, a portion thereof may obviously have a transparent insert whereby the liquid contents of the main chamber 2 thereof may be exposed to view, or, as shown, a suitable float element 3 may be provided at the lower end of a rod 4 which is rotatable in and slidable longitudinally through

a guide tube or bushing 5, which latter is fixedly secured in an axial opening in a closure cap or stopper 6 of a filler opening 7 provided in the top of the chambered body 1. As shown, the float rod 4 has a knob 8 fixed on its upper end, said knob 5 having a screw-threaded recess in its inner end portion, surrounding the adjacent portion of the rod in concentric spaced relation thereto and being normally screwed onto the projecting externally screw-threaded end portion 9 of the 10 guide tube or bushing 5, by which provision the knob may be turned to disengage it from said end portion 9 of the guide tube or bushing 5 so that the level of the liquid contents in the chamber 2 may be indicated by the distance of the 15 knob from the top of the body 1 due to the lifting of the rod 4 by the float element 3 (see Figure 1).

Obviously, the closure cap or stopper element 6 may be of any desirable type or form, but, as shown, it comprises a tapered plug which is fitted into a correspondingly flared opening 7 in the top wall of the chamber 2. Any suitable or desirable provision may be made for supporting the device in use, but inasmuch as it is more practical to mount the device on a wall or other support in a room or compartment where it is used, a supporting bracket 10 may be provided as shown in Figures 2, 4 and 6, said bracket being fastened to the wall or support by nails or screws, as at 11, the bracket being preferably provided with inturned convergent marginal flanges 12 or otherwise formed with undercut marginal walls which are obviously downwardly convergent so as to provide a tapered channel for the reception of a correspondingly tapered dovetail elongated lug or rib 13 which is formed integrally or otherwise provided on the body 1 of the device, by which provision the device may be readily placed and firmly supported on the bracket and readily removed therefrom, at will.

Just below the bottom 14 of the main chamber or reservoir 2, the body 1 is provided with a diametrical horizontal bore 15 extending from the front of the body to a point near the rear 45 face portion thereof, said bore being communicable with the chamber or reservoir 2 through an axial port 16. Fitted slidably in the bore 15 is a dispensing plunger element 17, said element being held against rotation in said bore 15 but 50 permitted limited longitudinal movement by having a lug or spline 18 which rides in a longitudinal groove 19 provided therefor in the bottom of the bore 15 near the outer end thereof. The outer end portion of the bore 15 is counterbored 55

and screw-threaded, as at 20, to receive therein a counterpart externally screw-threaded portion 21 of a flanged collar 22 through which the plunger element 17 slides. This collar 22 closes 5 the outer end of the groove 19 and affords a stop which the lug or spline 18 normally abuts to limit the position of the plunger element 17 which is urged outwardly by a spring element 23 interposed between the inner end of the plunger element 10 and the adjacent end wall of the bore 15, said spring element being constantly under tension and yieldable to permit inward movement of the plunger element as will be presently described.

15 The plunger element 17 is provided with an elongated chamber 24 having a port 25 which is normally in registration with the port 16 at the bottom of the main chamber or reservoir 2, by which provision the chamber 24 of the plunger element 20 is normally filled with liquid from the chamber or reservoir 2, said chamber 24 being of a predetermined size to receive a measured quantity of the liquid which is to be discharged into a vaporizing receptacle, as will now be described.

25 The body 1 of the device is provided in the bottom portion thereof, beneath the transverse bore 15, with a recess or pocket 26 for the reception of a counterpart vaporizing receptacle 27, the recess or pocket 26 being preferably in the form of an axial bore and the receptacle 27 being in the form of a generally cylindrical cup which is fitted removably but rather snugly within the bore 26, said receptacle 27 being preferably 30 made of a noncorrosive metal or other suitable material such as tempered glass, porcelain or the like.

35 Communication between the transverse bore 15 and the bore constituting the recess or pocket 26 is established through an axial passageway 28, said passageway being normally closed by the plunger element 17, the chamber 24 of said plunger element having a port 29 which is brought into registration with the passageway 28 when the 40 plunger element is moved inwardly against the tension of the spring element 23, it being noted that the relative sizes of the ports 25 and 29 of the plunger element and the distance between said ports being such that the port 25 is moved entirely out of registration with the port 16 of the main chamber or reservoir 2 before the port 29 moves into communicable registration with the passageway 28, and by the same token the port 29, on the outward stroke of the plunger 45 17, moves entirely away from the passageway 28 before the port 25 is again brought into communicable registration with said port 16. In this way, it is obvious that a measured quantity of liquid is delivered through the passageway 28 into the 50 receptacle 27 upon each actuation of the plunger element 17.

55 In practice, the capacity of the receptacle 27 is somewhat greater than that of the chamber 24 of the plunger element 17 so that, under ordinary 60 conditions, there is practically no possibility of an overflow of the liquid contents of the receptacle 27, but as a matter of precaution against such happening, in addition to fitting the receptacle rather tightly in the bore 26, the inner end wall 65 portion of the bore is provided with an annular groove 30 concentrically surrounding the passageway 28, said groove 30 receiving the inner end portion of the receptacle 27, which latter is also 70 preferably formed with a reduced annular ridge 75 portion 31 which is fitted in a corresponding

countergroove provided therefor in the bottom of the groove 30.

80 In order to releasably retain the receptacle 27 in the bore 26, it is preferable to provide the receptacle with concave recesses in its circumference to receive spring-pressed balls 32 which are contained in cylindrical radially disposed tubes or bushings 33 having restricted outer end openings which limit the normal protrusion of the balls beyond the adjacent face portions of the bore 26. There may be one or more of these latch ball elements, as desired, but for the particular purposes of the present invention it is preferable to provide three of these ball elements 32, one being located at one side of the bore 26 to 85 engage a recess 34 provided in the corresponding circumferential portion of the receptacle 27, and a companion pair of said ball elements being provided at the opposite side of the bore 26 to engage in a special pair of recesses 35 and 36, 90 respectively, provided therefor in the adjacent circumferential portions of the receptacle 27, said special pair of recesses 35 and 36 being provided with metal linings of electrical conductivity whereby circuit completing contact is made for 95 electrical heating elements to be presently more fully described, as well as serving as latching means for the releasable retention of the receptacle 27 in the bore 26. Obviously, to position the receptacle 27 in the bore 26, it is only necessary 100 to push the receptacle into place, whereupon the ball elements 32 snap into the respective recesses 34, 35 and 36, but to facilitate the removal of the receptacle it is preferable to countersink the outer end portion thereof, as at 37, and provide it with an undercut knob portion 38 at the center of the recess 37, or, obviously, any other suitable withdrawing means may be provided for the purpose.

105 Any suitable electrical heating means may be provided for vaporizing the liquid contents of the receptacle 27, but, as shown, it is preferable to provide a central disc-like electrode 39 which is mounted on the bottom of the receptacle, said electrode being exposed throughout the area of its top face as well as its peripheral portion and 110 connected by a wire 40 to the metal lining of the recess 35 in the circumference of the receptacle, said wire 40, of course, being preferably embedded in the adjacent body portion of the receptacle or otherwise located outside of the vaporizing chamber of the receptacle and suitably insulated therefrom. A second electrode 41, normally spaced from the electrode 39, is provided in the bottom portion of the receptacle, said electrode 41, as 115 shown, being in the form of a split ring extending in the circular corner portion where the cylindrical side wall of the receptacle merges with the bottom wall thereof and being connected by a wire 42 to the metal lining of the circumferential recess 36 of the receptacle.

120 Any suitable provision may be made for establishing electrical circuit connections between the metal linings 35 and 36 constituting the terminals of the wires 40 and 42, respectively, and a source of electrical energy. As shown, this is accomplished by embedding a connecting wire 43 in the base portion of the body 1 of the device between the closed end of the cylindrical bushing 33 and a tubular metal socket 44 of electrical conductivity which is secured in the bottom portion 125 of the bracket engaging rib 13 of the device (see Figure 6) and likewise connecting the companion bushing 33 to a companion socket 45 by a wire 46. When the device, as shown, is secured in the supporting bracket 10, said sockets 44 and 45 re- 130 75

ceive therein companion stud members 47 and 48, respectively, which are provided on a block 49 of insulating material which is secured to the lower portion of the bracket 10, said studs being formed integrally with enlarged socket portions 50 at their inner ends, said socket portions forming linings for recesses provided in the under side of the block 49 for the reception of split terminal contact members 51 and 52, respectively, provided 5 on a rectangular plug member 53 at the end of an electrical cord 54, which latter is provided at its opposite end with a regular conventional plug (not shown) which is obviously inserted in a conventional electrical outlet socket located at any 10 convenient place in a wall or floor. In this connection, it is obvious that as far as the present invention is concerned, the supporting bracket 10 for the device may be installed as a permanent fixture on a wall or other supporting base and be 15 provided with a conventional electrical outlet as a built-in element of the general wiring system 20 of the premises.

In the operation of the device, the plunger element 17 is pressed inwardly as hereinbefore described to deliver a measured quantity of the liquid contents from the main chamber or reservoir into the vaporizing receptacle 21, for general deodorizing or disinfecting purposes the quantity of liquid supplied to the receptacle 21 being equivalent to ordinary spoonful measurements. The liquid in the receptacle completes the electrical circuit between the electrodes 39 and 41, which latter becoming heated effect vaporization of the liquid and as soon as the entire contents have been vaporized and dissipated the electrical circuit is, of course, again broken and the heating elements 39 and 41 accordingly de-energized until a new charge of liquid is supplied in the receptacle.

40 To discharge the vapors from the receptacle 21
the latter, as shown, is provided with a pair of
outlet ports 55 in its rear upper portion, said
ports registering with outwardly flared discharge
passages 56 which are branched so that their
45 opened outer ends are located respectively on
opposite sides of the supporting rib 13 of the
body 1 of the device. It is here pointed out that
it is preferable to provide the plunger element
50 17 with a push button 57 at its outer end, said
push button as an entirety or at least its stem
portion 58 being of low heat conductivity or suit-
ably insulated from the body portion of the
plunger element. As shown, the stem portion of
55 the button is inserted in an axial bore in the outer
end of the plunger element and fastened in place
by a setscrew 59, the setscrew, of course, being
at least flush with the circumference of the
plunger or, preferably, sunk below the surface so
60 as not to interfere with the inward movement of
the plunger in the collar 22 and adjacent end
portion of the bore 15 in the body 1. By this
structural provision the original mounting, re-
moval and replacement of the plunger element is
65 facilitated in that the push button 57 is readily
detached from the plunger element for the origi-
nal placement and the replacement of the collar
21, which latter, when in place, serves as an end
thrust abutment for the lug or spline 18 on the
70 plunger element 17.

In practice, the knob 8 on the float rod 4, as well as the push button 57, is provided with a luminous coating or colored so as to be visible in the dark, and it is further noted that the body 1 of the device may be formed fancifully in any

modernistic or desirable contour, and that in the use of the device any suitable deodorizing or disinfecting liquid may be employed and dispensed into the vaporizing receptacle at any desired time.

While the device illustrated in the drawings embodies a practical adaptation of the invention, it is obvious that considerable modification may be made therein without departing from the spirit of the invention as defined in the appended claims. The invention, therefore, is not limited to the specific construction and arrangement shown. 10

What is claimed is:

1. A vaporizing device for the purpose described, comprising a vertically disposed body having a main upper liquid chamber and a lower vaporizing chamber, a cup-like receptacle removably inserted in said vaporizing chamber to constitute a liquid container and closure for the chamber, said receptacle having a vent opening communicable with a vapor discharge passage provided therefor in the adjacent body portion of the device, electrical heating means in said receptacle, and liquid transfer means interposed between the main liquid chamber and said vaporizing chamber, said liquid transfer means comprising a spring-projected chambered reciprocatory element normally closing communication between said main and vaporizing chambers but delivering a measured quantity of liquid from said main chamber to the vaporizing chamber by inward movement of the element.

2. In a vaporizing device of the character described, a supporting bracket, a vertically disposed body having a main upper liquid chamber, a vaporizing chamber formed by recessing the bottom portion of the body, said body having a transverse bore intermediate the main upper chamber and the recessed lower portion of the body, the body having a port opening between the main chamber and the upper side of the transverse bore and an aligned passageway between the lower side of the bore and the lower recessed portion of the body, a chambered plunger element fitted for endwise movement in said transverse bore, a spring element interposed between the inner end of the plunger element and adjacent end of the bore, said spring element yieldably holding the plunger element in normal projected position and reacting to return said element to such position after each actuation thereof, said plunger element having a port opening in its upper side in normal registration with the port opening in the body of the device and a port opening in its lower side forward of its upper port opening and also relatively forward of the passageway between the transverse bore and the recessed lower portion of the body of the device whereby, upon inward movement of the plunger element, communication between the chamber of the plunger element and the main upper chamber is cut off and a measured quantity of the liquid is delivered from the plunger chamber through the passageway to the lower recessed portion of the body, a cup-like receptacle removably inserted in the lower recessed portion of the body to constitute a liquid container and closure for the recess, spring-pressed latch means for releasably holding the receptacle in place, electrical heating means in said receptacle, portions of the circuit wiring for said electrical heating means being closed by the latching means for the receptacle, and means for venting said re-

ceptacle through the adjacent body portion of the device.

3. In a vaporizing device of the character described, a supporting bracket, a vertically disposed body detachably mountable on said supporting bracket, said body having a main upper liquid chamber, a lower vaporizing chamber formed by recessing the bottom portion of the body, said body having a transverse bore intermediate the main upper chamber and the recessed lower portion of the body, there being a port opening between the main chamber and the upper side of the transverse bore and an aligned passageway between the lower side of the bore and the lower recessed portion of the body, a chambered plunger element fitted for endwise movement but without rotation in said transverse bore, means for limiting the movement of the plunger element in opposite directions, said element being spring-projected and having diagonally opposed port openings whereby, in the normal projected position of the element, the chamber thereof is in communication with the main upper chamber of the device and communication is closed between the transverse bore and the passageway to the lower recessed portion of the body of the device, but upon inward movement of the plunger element communication between its chamber and the main upper chamber is closed and the contents of its chamber are delivered through the communicating passageway between said transverse bore and said lower recessed portion of the body, a cup-like receptacle removably inserted in the lower recessed portion of the body to constitute a liquid container and closure for the vaporizing chamber, said receptacle having a vent opening in communication with a vapor discharge passageway in the adjacent body portion of the device, the receptacle being circumferentially notched, spring-pressed latch elements in the adjacent body portion normally protruding in the lower recessed portion of the body for engagement in the circumferentially notched portions of the receptacle, and electrical heating means in said receptacle, portions of the circuit wiring for said electrical heating means being closed by the latching means for the receptacle and other portions of the wiring being electrically connected by detachable engagement of terminal elements provided on meeting portions of the supporting bracket and the attached body portion of the device.

4. The herein described vaporizing device, comprising a body having an upper main liquid chamber, a lower vaporizing chamber, and a transverse bore intermediate said upper and lower chambers, said bore and chambers having aligned openings for intercommunication therebetween, a spring-projected plunger element, said element being chambered and provided with diagonally opposed port openings whereby its chamber is normally in communication with the main

upper chamber of the device and communication with the lower vaporizing chamber is closed, but upon inward movement of the element communication with the main upper chamber is closed and the contents of the plunger chamber are delivered into the vaporizing chamber, said vaporizing chamber being formed by an axial bore in the bottom of the body of the device and a cylindrical cup-like receptacle removably fitted in said bore, said receptacle having a vent opening in its upper portion in communication with a vapor discharge passageway provided therefor in the adjacent body portion of the device, electrical heating means in said receptacle, and latch means for releasably securing the applied receptacle in place.

5. The herein described vaporizing device, comprising a vertically disposed body having a main upper liquid chamber, a lower vaporizing chamber, and means interposed between said chambers for delivering a measured quantity of liquid from the main upper chamber to the lower vaporizing chamber, at will, said vaporizing chamber being formed by a bore in the bottom of the body of the device with an axial inlet passageway at the inner end of the bore, the body being grooved annularly about the inlet passageway, a cylindrical cup-like receptacle fitted removably in said bore with its annular inner end portion received in the annular groove at the bottom of the bore, said receptacle having a vent opening in its upper portion in communicable registration with a vapor discharge passageway in the adjacent body portion of the device, electrical heating means in said receptacle, and latch means for releasably holding the inserted receptacle in place.

6. The herein described vaporizing device, comprising a vertically disposed body having an upper main liquid chamber and a lower vaporizing chamber, said vaporizing chamber being formed by a bore in the bottom of the body and having a detachable cup-like receptacle fitted in the bore to constitute a liquid container and closure for the vaporizing chamber, an electrical heating element in said receptacle, and means interposed between said upper main chamber and said vaporizing chamber for delivering a measured quantity of liquid from the main chamber to the vaporizing chamber, said means comprising a spring-projected chambered plunger element having diagonally opposed port openings whereby, in the normal position of the element, its chamber is in communication with the upper main chamber of the device and communication with the vaporizing chamber is closed, but upon inward movement of the element communication with the upper main chamber is closed and the contents of its chamber are delivered into the vaporizing chamber, and a non-heating push button mounted on the outer end of said plunger element.

LEWIS CATHCART.
